DESIGN FOR A COMBINATION COMPARTMENT CONTAINER OR SIMILAR ARTICLE

Ellis B. Strickler, Yorkana, Pa.

Application August 1, 1935, Serial No. 57,887

Term of patent 14 years

To all whom it may concern:

Be it known that I, Ellis B. Strickler, a citizen of the United States of America, residing at Yorkana, in the county of York, and State of Pennsylvania, has invented a new, original, and ornamental Design for a Combination Compartment Container or Similar Article, of which the following is a specification, reference being had to the accompanying drawings, forming part thereof, wherein

Fig. 1 is a perspective view of the combination compartment container, showing my design; and

Fig. 2 is a top plan view thereof.

I claim:

The ornamental design for a combination compartment container or similar article, as shown.

ELLIS B. STRICKLER.
